LIQUID APPLICATOR

Laura A. Chambers, St. Louis, Mo.

Application April 22, 1940, Serial No. 330,918

10 Claims. (Cl. 221—147)

The invention relates to devices whereby small quantities of liquid may be withdrawn from a bottle or like container and applied to a desired surface without pouring from the bottle. Devices of this nature are commonly used in applying shoe polish, hair dye, face cream, cleaning fluid, deodorants, etc.

One object of the invention is to accommodate the discharge of a desired quantity of liquid varying from a few drops to a steady stream.

Another object is to arrange for the withdrawal of the liquid from the container directly onto a dauber which may be charged with the liquid without inserting the dauber into the container.

These and other detail objects of the invention are attained by the structure illustrated in the accompanying drawing in which—

Figure 1 is a vertical section through a bottle and associated structure embodying one form of the present invention and showing all of the elements in the position and condition characterizing the beginning of a liquid applying operation.

Figure 2 is a similar section showing the operating bulb and associated parts compressed to force air into the bottle.

Figure 3 is a similar section showing the bulb released and partially filled with liquid which may be discharged by further compression of the bulb.

Figure 4 illustrates a modified form of the invention in which the liquid is to be applied by means of a dauber and showing the parts at the beginning of a dauber charging operation.

Figure 5 shows the same parts with the operating bulb compressed to force air into the bottle.

Figure 6 illustrates the same parts with the bulb released and the dauber charged with liquid.

Figure 7 is a detail section illustrating a different arrangement of the bulb and associated parts.

The bulb 1 shown in Figures 1, 2 and 3 has a general globular shape with a neck portion 2 adapted to receive and closely engage the neck 3 of a bottle 4 in which the liquid to be applied is normally contained. A hollow tube 5 of glass, rubber, or other material, projects from bulb 1 axially of bulb neck 2, and the exterior of the upper portion of tube 5 is tightly joined with the upper or inner end of bulb neck 2. An open-top cup-like partition 6 surrounds the upper end of tube 5 and the upper edge 7 of this partition is normally spaced from the opposing portion 8 of the top wall of bulb 1. Bulb 1 and partition 6 are formed of flexible material such as vul-

canized rubber which is readily deformable and possesses resiliency to return quickly to normal position when relieved from deforming pressure.

Assuming the bottle to be substantially filled with a liquid L and the bulb to be substantially filled with air A and having its normal contour, all as indicated in Figure 1, the pressure on the bulb top wall 8 distorts the contour of the bulb decreasing its volume and forces air downwardly through tube 5 discharging the same from the bottom of the latter where it will bubble upwardly, as indicated at B in Figure 2, and rise to the top of the bottle. As bulb wall 8 moves downwardly it contacts the upper edge of partition 7 and deforms the latter, as indicated in Figure 2. Upon release of pressure on bulb 1 the same returns to its normal position and the increased volume of its interior results in the pressure within the bulb and within the bottle being unbalanced so that the air in the upper portion of the bottle forces a quantity of liquid upwardly through tube 5 into cup 6 and, after the latter is filled, into the chamber 9 surrounding the cup, as indicated in Figure 3. Upon subsequent compression of bulb 1 liquid is discharged from chamber 9 through a vent 10 provided in the wall of the bulb. Ordinarily this vent will be too small to permit the air originally in the bulb to escape when pressure is first applied and will be too small to permit the bulb to be filled with air, instead of with liquid, when the first pressure is released. If desired, particularly if the bottle is almost full, shifting of liquid from the bottle to the bulb by the operations referred to above may be facilitated by placing a finger over vent 10 to prevent any outlet or inlet of air during the initial manipulation.

If desired, the bulb may be fitted with a nipple 11 around vent 10 to more clearly indicate the point of discharge and, if desired, a removable tube 12 of glass such as is used in the ordinary medicine dropper may be inserted through the nipple and removed for cleaning, etc.

The same general principle may be embodied in a somewhat different arrangement, as illustrated in Figures 4, 5 and 6, in which the liquid forced from the bottle, instead of being trapped in a chamber in bulb 15, is discharged against and trapped in a retaining member 16 removable from the bulb for application to a desired surface. Member 16 may consist of a sponge, cotton pad, brush or other material and is removably secured in the handle.

Bulb 15 has a neck portion 17 fitting around the bottle neck as previously described and the de-

vice includes a tube 18 corresponding to that previously described. The upper portion of the bulb is apertured at 19. A dauber handle 20 has a flanged portion 21 with a flexible edge 22, the diameter of the flange being greater than the diameter of aperture 19 so that when the dauber is pressed downwardly the flange will have a sealing contact with the bulb and the dauber handle and flange will become in effect a part of the top wall of the bulb. The shank 23 of handle 20 is substantially smaller in diameter than bulb aperture 19 but member 16 mounted on the lower end of the shank may slightly exceed the diameter of aperture 19 so that it will be squeezed slightly as it is passed through the aperture.

The handle may be grasped with the fingers and pressed downwardly from the position shown in Figure 4 to the position shown in Figure 5 in which position the volume of bulb 15 will be reduced and the air therein forced through tube 18 to the interior of the bottle where it rises to the top of the bottle as in the construction previously described. Upon release of pressure on the handle the bulb will return to its normal contour and the unbalanced pressure in the bottle and the bulb will result in liquid being forced upwardly through tube 18 and discharged against and around member 16 which may then be withdrawn from the bulb and applied to the surface to be treated.

Figure 7 illustrates an arrangement whereby the side of the bulb 25 is brought down directly to the bottle neck 26 and an inner wall 27 on the bulb extends over the rim of the bottle mouth to surround and mount tube 28. Otherwise the construction corresponds generally to that previously described.

The device has the advantage of avoiding the insertion of a stem or tube within a bottle and its removal from the bottle for use. The device may be substituted for the bottle cork and it is unnecessary to struggle with the cork before the contents of the bottle are available. If the device as described in Figures 1-3 is used for medicine or the like, there is no possibility of inserting a contaminated dispenser into the bottle, as is possible with the ordinary medicine dropper, and where the device as described in Figures 4-6 is used as a dauber, the sponge is firmly held close to the end when in use rather than on the end of a flexible wire.

In both forms of the invention liquid not actually used is readily retained and the device avoids the messiness which would attend the withdrawal of more liquid than is required for a given application.

The details of the construction may be varied otherwise than as described above without departing from the spirit of the invention and the exclusive use of such modifications as come within the scope of the claims is contemplated.

What is claimed is:

1. In a device of the class described, a bulb of resilient material, a hollow tube opening into the interior of the bulb and projecting therefrom for insertion into a fluid container, said bulb being compressible to force fluid therein through said tube and, upon release from pressure, to expand to normal contour and thereby take in fluid through said tube, a partition in said bulb and surrounding the inlet from said tube, the space between said partition and the side of said bulb being adapted to trap fluid drawn into said bulb through said tube, there being a vent in the side of said bulb for discharging trapped fluid inde-

pendently of said tube when the bulb is again compressed.

2. A device as described in claim 1 in which the partition comprises an open-top cup surrounding the adjacent end of the hollow tube.

3. A device as described in claim 1 in which the partition is formed of flexible material adapted to be deformed upon contact with the bulb when the latter is compressed.

4. In a device of the class described, a resilient bulb having a part arranged to fit around the neck of a bottle or like container, a hollow tube extending through said part and opening into the interior of the bulb, there being sealed contact

15 between the exterior of said tube and the inner portion of said part, a flexible partition in the bulb surrounding and spaced from the inner open end of said tube and extending above the same, there being a passageway between the upper edge

20 of said partition and the upper inner wall of the bulb, said partition and bulb cooperating to form a chamber for trapping fluid drawn through said tube, said bulb being apertured at the side of said partition opposite to said tube to discharge fluid so trapped.

5. In a device of the class described, a bulb of resilient material having an opening in its upper wall, a separable member including a handle, a radial disc thereon, and a shank depending from

30 said disc, said disc being arranged to close said opening and having a flexible edge to overlap the edge of said opening, there being a liquid absorbent sponge at the lower end of said shank, a hollow tube depending from the lower wall of said 35 bulb with its upper end opening into said bulb opposite to said sponge, and a depending neck on said bulb surrounding said tube and arranged to fit the mouth of a liquid container into which said tube may be inserted.

40 6. In a device of the class described, a bulb of resilient material having an opening in its top wall and a depending neck in its bottom wall adapted to receive the neck of a liquid containing bottle, there being a hollow tube communicating with the interior of said bulb and projecting through said bulb neck to be inserted in the liquid in the bottle, and a separable member applicable to said bulb to close the opening in the top wall thereof and through which pressure may be applied to said bulb to compress the same, said member

45 having a sponge element insertable within said bulb and positioned to be in the path of liquid discharged into said bulb by alternate compression and release of said bulb by manipulation of said member.

55 7. In a device of the class described, a collapsible chamber with walls of flexible material having one side arranged for the application of the chamber to a fluid container, a hollow tube with an unrestricted opening at its upper end into the bottom of the interior of the chamber and projecting from the chamber for insertion of its lower and unrestricted end into the fluid container, said chamber being collapsible under manual pressure to a flattened oblate form to force fluid therein through said tube, and being expandable to its normal contour, upon release from manual pressure, to thereby draw fluid from said container through said tube into said chamber, the device including means within said chamber forming a trap for fluid drawn into said chamber through said tube, said tube draining surplus untrapped fluid drawn into the chamber back into the container, and means independent of said tube for discharging the trapped fluid from the

60 8. In a device of the class described, a collapsible chamber with walls of flexible material having one side arranged for the application of the chamber to a fluid container, a hollow tube with an unrestricted opening at its upper end into the bottom of the interior of the chamber and projecting from the chamber for insertion of its lower and unrestricted end into the fluid container, said chamber being collapsible under manual pressure to a flattened oblate form to force fluid therein through said tube, and being expandable to its normal contour, upon release from manual pressure, to thereby draw fluid from said container through said tube into said chamber, the device including means within said chamber forming a trap for fluid drawn into said chamber through said tube, said tube draining surplus untrapped fluid drawn into the chamber back into the container, and means independent of said tube for discharging the trapped fluid from the

65 9. In a device of the class described, a collapsible chamber with walls of flexible material having one side arranged for the application of the chamber to a fluid container, a hollow tube with an unrestricted opening at its upper end into the bottom of the interior of the chamber and projecting from the chamber for insertion of its lower and unrestricted end into the fluid container, said chamber being collapsible under manual pressure to a flattened oblate form to force fluid therein through said tube, and being expandable to its normal contour, upon release from manual pressure, to thereby draw fluid from said container through said tube into said chamber, the device including means within said chamber forming a trap for fluid drawn into said chamber through said tube, said tube draining surplus untrapped fluid drawn into the chamber back into the container, and means independent of said tube for discharging the trapped fluid from the

70 10. In a device of the class described, a collapsible chamber with walls of flexible material having one side arranged for the application of the chamber to a fluid container, a hollow tube with an unrestricted opening at its upper end into the bottom of the interior of the chamber and projecting from the chamber for insertion of its lower and unrestricted end into the fluid container, said chamber being collapsible under manual pressure to a flattened oblate form to force fluid therein through said tube, and being expandable to its normal contour, upon release from manual pressure, to thereby draw fluid from said container through said tube into said chamber, the device including means within said chamber forming a trap for fluid drawn into said chamber through said tube, said tube draining surplus untrapped fluid drawn into the chamber back into the container, and means independent of said tube for discharging the trapped fluid from the

chamber to the exterior of the device and container, said trap-forming means being of flexible material readily deformable to accommodate collapsing of the chamber when manual pressure is applied to the exterior of the chamber.

8. In a device of the class described, a collapsible chamber having one side arranged for the application of the chamber to a fluid container, a hollow tube opening at one end into the interior of the chamber and projecting from the chamber for insertion of its other end into the fluid container, said chamber being collapsible under manual pressure to force fluid therein through said tube, and being expandable to its normal contour, upon release from manual pressure to thereby draw fluid from said container through said tube into said chamber, the device including a liquid-absorbent sponge member readily insertible into and removable from the chamber and forming a trap for fluid drawn into the chamber through said tube.

9. In a device of the class described, a collapsible chamber having one side arranged for the application of the chamber to a fluid container, a hollow tube opening at one end into the interior of the chamber and projecting from the chamber for insertion of its other end into the fluid container, said chamber being collapsible under manual pressure to force fluid therein through said tube, and being expandable to its normal contour, upon release from manual pressure to thereby draw fluid from said container through said tube into said chamber, the device including elements forming a trap for fluid drawn into said chamber through said tube, said tube being unobstructed throughout its length and draining surplus untrapped fluid in the chamber by gravity back into the container when manual pressure on the chamber is released, and means independent of said tube for discharging the trapped fluid from the chamber.

5 tube into said chamber, there being an opening in the upper portion of the chamber wall, a separable closure applicable to said latter-mentioned opening, and a liquid-absorbent member depending from said closure and constituting a trap for liquid drawn into the chamber through said tube as described, and being receivable in and removable from said chamber through said opening by application and detachment of said closure.

10 15 20 25 30 10. In a device of the class described, a collapsible chamber with walls of flexible material having one side arranged for the application of the chamber to a fluid container, a hollow tube opening at its upper end into the bottom of the interior of the chamber and projecting from the chamber for insertion of its lower end into the fluid container, said chamber being collapsible under manual pressure to force fluid therein through said tube, and being expandable to its normal contour, upon release from manual pressure to thereby draw fluid from said container through said tube into said chamber, the device including elements forming a trap for fluid drawn into said chamber through said tube, said tube being unobstructed throughout its length and draining surplus untrapped fluid in the chamber by gravity back into the container when manual pressure on the chamber is released, and means independent of said tube for discharging the trapped fluid from the chamber.
